REFINING AND BLEACHING FATTY ACID ESTERS

George Barsky, New York, N. Y., assignor to E. F. Drew & Co., Inc., New York, N. Y., a corporation of Delaware

No Drawing. Application February 24, 1951,
Serial No. 212,678

6 Claims. (Cl. 260—410.6)

The present invention is directed to fatty acids such as the neutral fatty acid esters of polyhydric alcohols and more particularly to a method for purifying such substances.

It has been customary in the production of such compositions for industrial or edible purpose, to first esterify the constituents to form the substantially neutral esters and then to subject the crude ester to a refining operation with the use of caustic alkali. Thereafter, there was a bleaching operation by means of an earthy material or the like. In many cases the bleaching was ineffective especially when the crude ester was of a relatively dark color. The loss in the alkali refining operation was often quite substantial. Some times a bleaching step was introduced wherein such compounds as chlorine dioxide were used. This added considerable expense to the refining operation, the chemicals were difficult to handle and close regulation of the operation was necessary.

The present invention is intended and adapted to overcome the difficulties and disadvantages inherent in prior treatments of the type described, it being among the objects of the present invention to provide a method of refining crude esters of fatty acids which is simple and effective, which results in adequate bleaching of the ester even if it is dark colored and in which the refining and bleaching is conducted in a single operation.

It is also among the objects of the present invention to provide a method of refining esters which is applicable to both liquid and solid esters of the type described, adapted for edible and industrial purposes on a large scale without the necessity for a double set of equipment for conducting the operation.

The present invention is based upon the use in the refining operation of hydrogen peroxide together with alkaline agents. The crude ester, which may be a glyceride ester of fatty acids or the polyglycol esters of such acids, is mixed with an alkaline compound in the dry state. The alkaline compound is an alkali metal carbonate. The mixture is heated with agitation to a temperature of from 80° to 110° C. in the presence of a 30% aqueous solution of hydrogen peroxide. The amount of hydrogen peroxide used is about .5 to 2.5% by weight of the crude ester being treated. An excess of alkali metal carbonate is then added in amounts sufficient to neutralize all of the free fatty acid present in the crude ester and the mixture is agitated, the temperature being above room temperature but usually below the temperature of treatment with the hydrogen peroxide. The mixture is then allowed to settle and the aqueous layer containing soaps of the fatty acids is drawn off from the bottom of the refining kettle. The refined ester is then dried and is ready for use.

The following is a specific example of the operation of the present invention.

Example

There is provided a crude ester which consists of a mixture of fatty acids of which capric and caprylic are the principal constituents, as described in the co-pending application Serial No. 221,522, filed April 17, 1951, of George Barsky and George Zinzalian, and entitled "Caprylic-Capric Ester Plasticizer."

4,000 lbs. of the above crude ester are mixed with

2

dry sodium carbonate in an amount in excess of that required to neutralize all of the free fatty acids contained therein. The mixture is heated to about 50° C. with agitation in order to disperse the soda ash throughout the crude ester. There is then added 80 lbs. of a 30% aqueous hydrogen peroxide solution while continuing the agitation for several hours and heating the mixture to about 90° C. This results in a combined bleaching and refining and the product is then allowed to settle over a period of several hours or until a clear line of demarcation is observed between the lower aqueous soap solution and the upper layer of refined ester.

The soap solution is withdrawn from the bottom of the refining kettle, the refined ester is heated to about 110° C. in the presence of a vacuum to remove traces of water and it is filtered through bleaching earth or activated carbon. This results in a removal of suspended matter and a deodorization of the refined ester, which has the following analysis.

ffa (as oleic)	0.15
Color (Lovibond Red 5 1/4" Col)	10/1.2
Sap value	272
Ash	0.0015
25 Acetyl value	13.0
IV	0.4

There are a number of advantages inherent in the present invention in that in a single operation in a single piece of equipment a high degree of refining and bleaching is obtained. The equipment is standard and no highly skilled labor or supervision is required in the operation. The results are readily duplicated by the ordinary workman in a series of refining operations. Considerable time and expense is saved in conducting the two operations as a single unit. The loss of ester in the soap layer is minimized and in following the details of the bleaching operation, a highly effective result is obtained in a relatively short time.

Although the invention has been described setting forth a single specific embodiment thereof, the invention is not limited thereto as various changes in the details may be made without departing from the principles herein set forth. For instance, other fatty esters than those specifically set forth herein may be treated by the present process. The fatty acids may be obtained from animal or vegetable oils or from other sources such as those acids formed by synthetic methods. For instance, if an ester has more or less color to be removed therefrom, correspondingly more or less hydrogen peroxide is used. The temperatures of the operation may be varied within the stated limits with good results, depending upon the character of the operation being conducted.

These and other changes may be made in the details of the operation within the spirit of the invention, which is to be broadly construed and not to be limited except by the character of the claims appended hereto.

I claim:

1. A method of simultaneously alkali refining and bleaching crude substantially neutral and water insoluble fatty acid esters of polyhydric alcohols taken from the class consisting of glycerol and polyglycols which comprises adding to said ester an amount of a dry alkali metal carbonate at least sufficient to neutralize all the free fatty acids contained therein, heating and agitating said mixture, thereafter introducing from 0.5 to 2.5% by weight of said ester of a 30% aqueous hydrogen peroxide solution, heating said mixture from 80° C. to 110° C. while agitating the same to cause bleaching, allowing the mixture to settle into two layers and recovering the ester.

2. A method of simultaneously alkali refining and bleaching crude substantially neutral and water insoluble fatty acid esters of polyhydric alcohols taken from the class consisting of glycerol and polyglycols which comprises adding to said ester an amount of a dry alkali metal carbonate at least sufficient to neutralize all the free fatty acids contained therein, heating and agitating said mixture, thereafter introducing from 0.5

to 2.5% by weight of said ester of a 30% aqueous hydrogen peroxide solution, heating said mixture from 80° C. to 110° C. while agitating the same to cause bleaching, allowing the mixture to settle into two layers and recovering the ester, and then heating said ester above 100° C. in a vacuum to remove traces of water.

3. A method of simultaneously alkali refining and bleaching crude substantially neutral and water insoluble fatty acid esters of polyhydric alcohols taken from the class consisting of glycerol and polyglycols which comprises adding to said ester an amount of a dry alkali metal carbonate at least sufficient to neutralize all the free fatty acids contained therein, heating to about 50° C. and agitating said mixture, thereafter introducing from 0.5 to 2.5% by weight of said ester of a 30% aqueous hydrogen peroxide solution, heating said mixture from 80° C. to 110° C. while agitating the same to cause bleaching, allowing the mixture to settle into two layers and recovering the ester.

4. A method of simultaneously alkali refining and bleaching crude substantially neutral and water insoluble fatty acid esters of polyhydric alcohols taken from the class consisting of glycerol and polyglycols which comprises adding to said ester an amount of a dry sodium carbonate at least sufficient to neutralize all the free fatty acids contained therein, heating to about 50° C. and agitating said mixture, thereafter introducing from 0.5 to 2.5% by weight of said ester of a 30% aqueous hydrogen peroxide solution, heating said mixture from 90° C. to 95° C. while agitating the same to cause bleaching, allowing the mixture to settle into two layers and recovering the ester.

5. A method of simultaneously alkali refining and bleaching crude substantially neutral and water insol-

uble fatty acid esters of polyhydric alcohols taken from the class consisting of glycerol and polyglycols which comprises adding to said ester an amount of a substantially dry sodium carbonate at least sufficient to neutralize all the free fatty acids contained therein, heating to about 50° C. and agitating said mixture, thereafter introducing 2% by weight of said ester of a 30% aqueous hydrogen peroxide solution, heating said mixture from 90° C. to 95° C. while agitating the same to cause bleaching, allowing the mixture to settle into two layers and recovering the ester.

10 6. A method of simultaneously alkali refining and bleaching crude substantially neutral and water insoluble fatty acid esters of polyhydric alcohols taken from the class consisting of glycerol and polyglycols which 15 comprises adding to said ester an amount of a dry sodium carbonate at least sufficient to neutralize all the free fatty acids contained therein, heating to about 50° C. and agitating said mixture, thereafter introducing 20 2% by weight of said ester of a 30% aqueous hydrogen peroxide solution, heating said mixture from 90° C. to 95° C. while agitating the same for several hours to cause bleaching, allowing the mixture to settle into two layers and recovering the ester, and then 25 heating said ester from 100° C. to 110° C. in a vacuum to remove traces of water.
